ERWIN J. ROBERTS, OF NEWARK, NEW JERSEY

SWIMMING PEDAL

Application filed September 23, 1931. Serial No. 564,565.

This invention relates, generally, to swimming pedals or devices adapted to be attached to the feet of swimmers for facilitating their movement through the water; and the invention has reference, more particularly to a novel construction of swimming pedal.

Swimming pedals, as heretofore generally constructed, have never become very popular because of their excessive weight and cumbersome construction, rendering it exceedingly difficult to use the same for any length of time without the user becoming unduly tired.

The principal object of the present invention is to provide a novel swimming pedal which is easily manipulated by the swimmer in use, and which enables the swimmer to exert a relatively great propelling effect with a minimum of effort.

Another object of the present invention lies in the provision of a novel swimming pedal which is of light, strong construction and is easily attached to the feet of the swimmer.

Still another object of the present invention lies in the provision of a novel swimming pedal having hinged wing members which automatically collapse or move into relative folded positions when the swimmer's foot is drawn forwardly, so that the pedal offers a minimum of resistance to forward movement of the foot, but which wing members immediately expand or open into their extended operative positions upon the initiation of the backward movement of the foot, to thereby exert a thrust against the water and effect the forward propulsion of the swimmer.

Other objects of the invention, not at this time more particularly enumerated, will be clearly understood from the following detailed description of the same.

The invention is clearly illustrated in the accompanying drawing, in which:

Fig. 1 is a plan view of the novel swimming pedal of the present invention with the swimming shoe detached therefrom, and with a modified form of wing elements being shown in dot and dash lines.

Fig. 2 is a sectional view taken substantially along line 2-2 of Fig. 1 and showing the manner of attaching the shoe to the pedal.

Fig. 3 is a sectional view taken substantially along line 3-3 of Fig. 2; and

Figs. 4 and 5 are perspective views illustrating the operation of the swimming pedal.

Similar characters of reference are employed in all of the above described views, to indicate corresponding parts.

Referring now to said drawing, the reference numeral 1 designates the novel swimming pedal of the present invention as a whole. The swimming pedal 1 comprises a central, longitudinally extending, rigid body member consisting of a narrow main plate 2 having a plurality of spaced hinged knuckles 3 formed along its side edges. The main plate 2 is illustrated as stiffened by an under-plate 4 which lies adjacent the under-surface of plate 2 and is held rigidly to plate 2 as by rivets 5. The rivets 5 extend upwardly through under-plate 4, main plate 2 and through transversely extending reinforcing members or bars 6 and 7. The reinforcing bar 6 is positioned near the forward end of the body member, whereas the reinforcing bar 7 is positioned near the rear end of the body member. The reinforcing bar 6 is preferably of greater length than the reinforcing bar 7, as illustrated in the drawing, and these reinforcing bars are secured fixedly to the body member consisting of plates 2 and 4 by means of the rivets. Reinforcing bars 6 and 7 serve to strengthen and reinforce a pair of similar wing members 8 when these wing members are in their extended, working positions.

Wing members 8 are provided with hinge knuckles 3' for cooperating with the hinge knuckles 3 of main plate 2. Hinge pins 9 extend through the aligned openings of hinge knuckles 3 and 3' for hingedly connecting the wing members 8 with the main plate 2 of the body member. Coil springs 11 surround an intermediate portion of the hinge pins 9 and are situated between consecutive spaced hinge knuckles 3 provided on main plate 2. One end portion of each of the springs 11 engages the body member and the other end portion of the spring engages a wing member 8. Springs 11 are of sufficient strength to normally maintain the wing members 8 in

their horizontal, mutually aligned positions shown in Fig. 3. In other words, these spring members have sufficient tension to normally support the weight of the wing members 8 but will yield to permit downward swinging movement of the wing members toward each other when the pedal is pulled forwardly or upwardly through the water, as illustrated in Fig. 5, the water pressure serving to collapse or turn the wing members into folded relation.

The hinge pins 9 are preferably provided with heads 10 which are located at their rear ends only so that these hinge pins may be removed, for example, to enable replacement of the springs 11 should these springs break in use. Wing members 8 are illustrated as made of sheet metal and are provided with a turned-over bead or flange 12 extending along their marginal edges to stiffen these wing members while providing a rounded edge portion to prevent the same from injuring the swimmer should these wing members accidentally strike the legs of the swimmer in use.

In order to attach the pedal to the swimming shoe, such as the shoe 13, shown in the drawing, bolts 14 are provided, which bolts have large, substantially flat heads 15 for engaging the inner sole of the shoe 13. Bolts 14 extend through aligned apertures provided in the body member and reenforcing bars 6 and 7 and through apertures provided in the sole of the shoe 13, as especially illustrated in Figs. 2 and 3.

In use, the swimmer in attaching the shoes 13 to his feet also secures the pedals 1 in proper relative position and centrally upon his feet. Since the springs 11 act to normally maintain the wing members 8 horizontal, the swimmer may walk around on the beach with the pedal wing members in the positions shown in Figs. 2 and 3. On entering the water, the swimmer, upon making a forward or non-power stroke of his feet, causes the water pressure upon wing members 8 to collapse or fold these wing members inwardly into their folded out of the way positions shown in Fig. 5, so that the pedals move through the water with negligible resistance. At the end of the forward stroke of the feet, the wing members will automatically unfold into operative aligned positions owing to the action of springs 11, so that when the swimmer makes a back-stroke, as illustrated in Fig. 4, these wings are distended and enables the swimmer to obtain a powerful forward thrust, forcing him at a rapid pace through the water.

Preferably the novel swimming pedals of the present invention are largely made of aluminum or some other light metal or alloy so as to have a minimum weight, though having considerable stiffness owing to the presence of the rigid body member, the beads 12 and the reenforcing members or bars 6 and 7.

It will be apparent that the wing members 8 may have various shapes other than that shown in the drawing. For example, these members may be attenuated as shown in the dot and dash lines in Fig. 1 to thereby provide a speed swimming pedal for use especially by speed swimmers. It will be obvious that the novel swimming pedals may be made in various sizes to suit various sizes of shoes.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. A swimming pedal comprising a rigid flat longitudinally extending body member having spaced hinge knuckles formed all along the sides thereof, wing members positioned at the sides of said body member, said wing members having hinge knuckles interfitting with the hinge knuckles of said body member, hinge pins interconnecting the cooperating hinge knuckles of said wing members and said body member, coil torsion springs surrounding said hinge pins, each of said torsion springs having one of its ends engaging said body member and its other end engaging a respective one of said wing members, for urging said wing members into oppositely extended, aligned positions, and a pair of spaced transverse reenforcing bars secured to said body member and overlying said wing members for reenforcing the latter when in their oppositely extended positions.

2. A swimming pedal comprising, a rectangular longitudinally extending, substantially flat, sheet metal, body member, substantially flat, sheet metal, wing members hingedly connected to the opposite side edges of said body member, the hinged connections between said body member and said wing members consisting of interfitting hinge knuckles extending all along the length of said body member, and a pair of hinge pins extending along the length of said body member for interconnecting said hinge knuckles, resilient torsion spring means carried by said hinge pins and acting upon said wing members and said body member for urging said wing members upwardly about their hinged connections with said body member, a pair of spaced reenforcing cross bars secured to said body member and extending transversely thereof into overlying relation with respect to said wing members for limiting the upward turning movement of the latter, said resilient torsion spring means being of just sufficient strength to support the weight of said wing members and serving to normally

hold said wing members in abutting relation to said cross bars, and fastening means secured to said body member and extending upwardly therefrom for securing a swimming 5 shoe to said body member.

In testimony, that I claim the invention set forth above I have hereunto set my hand this 3rd day of September, 1981.
